PRIMER AND METHOD OF MANUFACTURING AND LOADING THE SAME

Walter P. Hill, Detroit, Mich., assignor to Calumet and Hecla Consolidated Copper Company, Calumet, Mich., a corporation of Michigan

Application July 12, 1943, Serial No. 494,387

4 Claims. (Cl. 86—23)

This invention relates to primers for use in projectiles and to the method of manufacturing and loading the same.

One of the principal objects of this invention is to provide an improved primer, the body and fire tube of which may be produced from tubing, thereby simplifying the construction and reducing the number of operations required to produce and assemble the same.

Another primary object of this invention is to provide a simplified method of loading the primer whereby the assembly of the fire tube with the primer body is greatly facilitated.

Many other objects and advantages of this invention will become more apparent as this description proceeds, especially when considered in connection with the accompanying drawing, wherein:

Figure 1 is a sectional elevational view of a primer constructed in accordance with this invention.

Figure 2 is a sectional elevational view showing the method of closing one end of the fire tube and of the primer body.

Figure 3 is a sectional view showing the base and fire tube assembled.

Figure 4 is a sectional view of the primer body loaded and ready for assembly with the fire tube and base, and

Figure 5 is a sectional view showing the method of assembling the fire tube with the primer body.

Referring first to Figure 1, it will be noted that the primer comprises a body 10 having an integral closed end 11 and an open opposite end through which the body is charged with a powder or other compound, which end is closed by a base 12. The base 12 is provided with a reduced externally threaded portion 13, with an externally threaded portion 14 of larger diameter forming an annular shoulder 15 and with a head 16.

Reference character 18 indicates a fire tube having a closed end 19. The open end of the fire tube 18 is externally threaded to engage a tapped bore 20 in the base 12.

The primer body 10 is provided with a plurality of holes or apertures 21 which permit the charge in the primer, when the latter is set off, to escape to ignite the propelling charge in the casing of the projectile.

The fire tube is likewise provided with a plurality of holes or apertures 22 which permit the charge in the fire tube, when the same is set off, to escape and ignite the charge in the main primer body.

Both the primer body 10 and the fire tube 18

are made of tubing, preferably drawn seamless tubing. Thus both of these elements of the primer may be made of any desired length by cutting the same off lengths of tubing.

5 It will be noted that the primer body 10 has an integral closed end 11 and that the fire tube 18 has an integral closed end 19. The integral closed end 11 eliminates the necessity of using a separate plug to close the same as has heretofore 10 been the practice. In accordance with prior practices, such plugs were produced on a screw machine and the end of the primer body had to be drilled, counterbored, and tapped to receive the plug. Also, the plug had to be assembled with the 15 end of the primer body and thereafter the counterbored portion was crimped over to hold the plug in place. These operations are eliminated by the use of an integral closed end as herein disclosed.

20 The fire tube is also provided with an integral closed end 19 which is an improvement over prior methods wherein the end of the fire tube was closed by flattening the same.

The closed ends 11 and 19 are preferably, al- 25 though not necessarily, accomplished by the method and means described in my Patent No. 2,313,474, dated March 9, 1943, by means of the tool illustrated in Figures 8, 9 and 10 of said patent.

30 As shown in Figure 2 heretofore this tool 23 is provided with a spindle 24 so that the same may be attached to a rotatable member for rotating the tool. The tool is provided with an opening 25 of sufficient diameter to receive the end of the tube from which either the primer body or fire 35 tube is made, as the tube is forced into engagement with the tool and into the semi-spherical shaped cavity 26 formed therein. The end of the opening 25 adjacent the cavity 26 is preferably, 40 although not necessarily, formed with a continuous annular portion 27 which gradually decreases in cross-section in the direction of the cavity and which exerts a reducing pressure continuously around the entire circumference of the tube to progressively heat the same to a plastic or easily workable condition. The cavity 26 is provided with a relief portion 28 which permits successive portions of the stock to deform thereinto during the reducing operation, and prevent seizure between the tube and tool due to thermal 45 expansion of the tube.

As stated, the tool and tube are relatively rotated and moved axially toward one another. This results in a closing-in of the tube as shown, until the end is completely closed. By continued

relative movement of the tube and tool toward one another, the tube wall at the end may be thickened as illustrated at 11 and 19.

Before filling the fire tube 18 with powder, it is customary to insert therein a sleeve or cylindrical envelope of paper. The fire tube after being charged or filled with powder (not shown) is assembled with the base 12 by screwing the threaded end of the fire tube into the tapped bore 20.

In Figure 4 the main primer body 10 is shown as charged with a predetermined amount of powder or other compound P, sufficient to fill the primer body to the desired extent when the fire tube is in place. The customary sleeve or cylindrical envelope of paper is not shown. The next step is to assemble the fire tube and base with the main primer body. Inasmuch as the primer body is substantially filled with powder, some resistance is encountered in inserting the fire tube 18 into the primer body and through the charge of powder therein. To simplify and facilitate this assembly operation, I provide a stopper 29 for the powder in the form of a disc of paper or the like. This stopper 29 is inserted into the open end of the primer body 10 in engagement with the tapped portion 17 and is provided with an aperture 30 just large enough to receive the fire tube 18. The end of the fire tube 18 is then inserted into the aperture 30 and the primer parts are turned into an upright position as shown in Figure 5. Therefore, as the fire tube is shoved into the primer body, the powder falls downwardly around the fire tube offering little or no resistance to the entrance of the fire tube and during this operation the stopper, of course, prevents the powder from spilling out of the primer body. As soon as the reduced portion 13 of the base comes into engagement with the stopper 29, it is forced into the primer body and dislodged from the threads or tapped portion 17 whereupon the reduced portion 13 of the base may be screwed home into the tapped portion 17. The dislodged stopper 29 is shown in its dislodged position in Figure 1.

What I claim as my invention is:

1. The method of loading and assembling primers of the class described which consists in introducing a charge of powder into the primer body through the open end thereof, placing an apertured stopper in said open end, inserting the end of a fire tube through said aperture, and completing the insertion with the parts in a position wherein the charge of powder will flow by gravity around said fire tube permitting ready insertion thereof.
- 15 2. The method of loading primers having a primer body open at one end and a fire tube to be inserted therein through said open end which comprises, introducing a charge of powder into the primer body through the open end thereof, placing an apertured stopper in said open end, inserting the end of the fire tube through said aperture, and continuing its inward movement while in a position for the charge to flow around the same by gravity.
- 20 3. The method of loading primers having a primer body charged with powder and a fire tube adapted to be inserted therein through an open end thereof which consists in inserting an apertured stopper in said open end, inserting the fire tube into the aperture of the stopper, inverting the primer body and pressing the fire tube into said primer body while in position wherein the powder will flow by gravity around said tube.
- 25 4. The method of loading and assembling primers having a primer body provided with a threaded open end, and a fire tube adapted to be inserted into said body with a base adapted to be engaged with said threaded end, comprising, introducing a charge of powder into the primer body through its open end, placing an apertured stopper in said threaded end, inserting the end of the fire tube into said aperture, and completing the insertion with said stoppered end downward, said stopper being dislodged when said base engages said threaded end.
